EXTENSION LIGHT

Reginald H. Carter, Doylestown, Pa.

Application March 20, 1951, Serial No. 216,643

2 Claims. (Cl. 240—8.16)

(Granted under Title 35, U. S. Code (1952),
sec. 266)

1

The invention described herein may be manufactured and used by or for the Government of the United States of America for governmental purposes without the payment of any royalties thereon or therefor.

This invention relates to improvements in portable lighting devices and more particularly pertains to improvements in extension lamps adapted for use in aircraft cockpits, gun turrets, and for like uses.

Extensions lamps theretofore employed have been bulky, heavy, cumbersome in use and subject to frequent breakdown in service. The provision of focusing means and the external switching means employed have increased such disadvantages, particularly in uses where the operator must wear gloves or mittens.

The principal object of this invention is to provide an extension lamp that is simple in construction, of convenient size, light in weight, and sturdy and facile in use.

Another object is to provide an extension lamp that can be manipulated facilely for focusing and for switching on or off, and can provide such operations readily under extreme service conditions.

A further object is to provide an extension lamp that can emit a red light and a white light successively and wherein the size of the white light emitted can be varied facilely.

Still another object is to provide an extension lamp having a cam-actuated on-off switch that is protected adequately against entry thereon of foreign substances that can be encountered during extreme service conditions.

Other objects and many of the attendant advantages of this invention will be readily appreciated as the same becomes better understood by reference to the following detailed description when considered in connection with the accompanying drawing wherein

Fig. 1 is a plan view of an extension lamp, partly broken away to show certain features of construction, showing a preferred embodiment of the invention;

Fig. 2 is a section taken on the line 2—2 of Fig. 1;

Fig. 3 is a plan view of the extension lamp shown in Fig. 1, partly broken away, showing the device in fully retracted position;

Fig. 4 is a section taken on the line 4—4 of Fig. 1; and

Fig. 5 is a section taken on the line 5—5 of Fig. 1.

Similar numerals refer to similar parts throughout the several views.

2

The lamp socket and switch mount of the device comprises a generally cylindrical member 11 made of a dielectric such as hard rubber or Bakelite. Said member 11 comprises a cylindrical butt portion 13, an integral medial semi-cylindrical portion 15, adapted to carry the cam and switch members hereinafter described, and an integral cylindrical head portion 17 adapted to carry the lamp socket hereinafter described, so that the end walls 19 and 21 of the butt portion 13 and the head portion 17 respectively, with the flat 23 of the medial portion 15, define a transverse central slot. The medial portion 15 and the head portion 17 define a cylinder of smaller diameter than that defined by the butt portion 13 so that the peripheral portion of the wall 19 provides an abutting shoulder for the sliding tube assembly hereinafter described.

Lamp socket 25, which carries lamp 27, is seated in a bore 29 extending axially through the head portion 17 and extending partly into medial portion 15. The terminals of said socket 25 are a stepped lug 29' secured to the axial pin 31 of said socket and extending over a portion of the flat 23 and a washer 33 having an integral lug 35 secured to said socket in contact with the shell 37 thereof and insulated from the pin 31.

Strap 39 extends over stepped lug 29' and is fastened upon flat 23 by screws 41 and 43, thereby retaining said lug and the socket 25 in position. Moving contact 45 is soldered upon said strap 39, the resilient arm of said contact extending rearwardly towards the butt portion 13. Stationary contact 47 is fastened upon flat 23 by screw 49, the contacts 45 and 47 being so disposed as to be closed normally.

Cam 51 is made of a dielectric material and is carried rotatably on screw 43. Said cam 51 is so dimensioned and shaped that a portion of said cam extends to the diametral limit of butt portion 13 when contacts 45 and 47 are closed, and so that rotation of said cam to a position within such diametral limit causes said cam to move contact 45 out of engagement with contact 47.

Grommet or fitting 53 is threaded in a bore 55 tapped axially in the end of butt portion 13. A bore 57 communicates between bore 55 and wall 19 so that a first conductor 59 can be led from the screw 49 of contact 47 through said bore 57 and fitting 53, and a second conductor 61 can be led from lug 35 through said bore 57 and fitting 53, said conductors 59 and 61 being connected to a suitable source of current.

The sliding tube assembly of the device comprises a tube 63 adapted to fit slidably over head

portion 17 and medial portion 15 and to abut the peripheral portion of the wall 19, so that said tube 63 can rotate said cam 51 and thereby move contact 45 out of engagement with contact 47. The head portion 65 of said tube 63 is of enlarged diameter to provide a shoulder 67 for abutment of the outer shell or sleeve hereinafter described. A triangular window 69 is cut in the mid portion of said tube 63, the base of such triangle lying normal to the longitudinal axis of said tube and the apex of such triangle extending towards the head portion 65. Red glass lens 71 is secured in the end of head portion 65 by retainer ring 73.

To secure the sliding tube assembly on the cylindrical member 11 and permit relative sliding of said assembly and said member, a slot 75 extends along substantially the length of the head portion 17 and medial portion 15 of said member 11, and carries a slug 77 slidably therein. Countersunk screw 79 passes through the wall of said tube 63, proximate the end of said tube distal head portion 65, and is threaded into said slug 77. Thus member 63 can be retracted to the position shown in Fig. 3 to press the cam 51 against contact 45 and break the circuit, or can be extended to the position shown in Figs. 1 and 2 to be disengaged from the cam 51, to permit contacts 45 and 47 to engage, and to present the lamp 27 at the window 69.

The outer shell of the device comprises a tube 81 fitted slidably over tube 63 and butt portion 13, said tube 81 being secured to said butt portion 13 by setscrews 83 and abutting shoulder 67 when said tube 63 is retracted fully, as shown in Fig. 3.

In order to restrain movement of the tube 63 relative to tube 81, a suitable means to increase friction between tube 63 and member 11 is provided. Such means can be a flat steel spring 85 that is held in a milled slot 87 in the head portion 17 by a screw 89 and bears against the inside of tube 63.

In the operation of the device, alternating current from a suitable source is fed to the lamp 27 through conductor 59, contact 47, contact 45, strap 39, lug 29' and pin 31 successively, and is fed to the said lamp 27 through conductor 61, lug 35 and shell 37 successively. (Obviously, direct current could be employed through the same circuit.) It is apparent, then, that the making or breaking of contacts 45 and 47 control illumination of the lamp.

Such contacts are broken when tube 63 is in fully retracted position, said tube 63 pushing cam 51 inward to move contact 45 away from contact 47. When tube 63 is advanced a distance sufficient to clear cam 51, said cam 51 is pressed outwardly by contact 45 against tube 81, and in such position contact 45 engages contacts 47 to complete the circuit. In such position of the elements of the device, light is filtered through the red lens 71 and affords the conventional "safety" light.

When tube 63 is advanced somewhat further from its telescoping relation to tube 81, suitable focusing of the light emitted is effected. When tube 63 is advanced still further, a pin point of white light is emitted through the now exposed apex of the triangular window 69. With continued advance of the tube 63, the size of the triangle exposed beyond the end of tube 81 increases until a maximum is reached with exposure of the entire window.

It is thus apparent that the subject device provides an aircraft cockpit and gun turret extension lamp that is compact, light in weight, sturdy and facile in operation, and adapted to provide conveniently both a filtered and focused safety light and to pass "white" light that can be varied from a pin point of illumination to full opening. In the structure disclosed, the safety light is illuminated first, a desirable and at times essential feature, and the simple switch means provided is well protected mechanically.

Obviously many modifications and variations of the present invention are possible in the light of the above teachings. It is therefore to be understood that within the scope of the appended claims the invention may be practiced otherwise than as specifically described.

I claim:

1. An extension light comprising a cylindrical member carrying a lamp in one end thereof and a switch having a spring contact in a transverse central slot thereof, means to supply current to said lamp through said switch, a cam mounted on said member in said slot, said cam being urged normally partly beyond said slot by said contact and being adapted to move said contact out of closed circuit position when depressed into said slot. A first tube mounted on and encasing said member, a second tube carried slidably within said first tube and over said member, said second tube having a lens in one end thereof and a triangular aperture in the wall thereof, said aperture being in a position to reveal an apex thereof initially upon outward movement of said second tube, said cam being depressed into said slot during inward movement of said second tube, and means to limit sliding of said second tube relative to said member.

2. An extension light comprising a cylindrical member carrying a lamp in one end thereof and a switch having a spring contact in a transverse central slot thereof, means to supply current to said lamp through said switch, a cam mounted on said member in said slot, said cam being urged normally partly beyond said slot by said contact and being adapted to move said contact out of closed circuit position when depressed into said slot, a first tube mounted on and encasing said member, a second tube carried slidably within said first tube and over said member, said second tube having a filtering lens in one end thereof and a triangular aperture in the wall thereof, said aperture being in a position to reveal an apex thereof initially upon outward movement of said second tube, said cam being depressed into said slot during inward movement of said second tube, and means to limit sliding of said second tube relative to said member.
